UNITED STATES PATENT OFFICE.

JOHN B. MURRAY, OF BROOKLYN, E. D., ASSIGNOR TO M. NICHOLS JOHNSON,
OF NEW YORK, N. Y.

PARALLEL GAGE FOR PAPER-CUTTERS.

SPECIFICATION forming part of Letters Patent No. 240,921, dated May 3, 1881.

Application filed September 11, 1880. (No model.)

To all whom it may concern:

Be it known that I, JOHN B. MURRAY, of Brooklyn, in the State of New York, have invented an Improved Parallel Gage for Paper-Cutting Machines, of which the following is a specification, reference being had to the annexed drawings, in which—

Figure 1 is a side elevation of my improved parallel gage. Fig. 2 is a plan view of the same. Fig. 3 is an end view of the same. Fig. 4 is a central vertical section through my improved parallel gage, showing also the paper-gage, clamp, and knife in section.

My invention relates to an improved parallel gage for use in connection with paper-cutting machines, for the purpose of cutting narrow strips of paper, labels, &c.; and it consists in an improved compressible parallel gage composed of an upper and lower plate attached together at each side by diagonal pivoted links, provided with suitable cross-rods and springs for separating the said plates while they remain parallel to each other and without changing their positions lengthwise.

My invention also consists in the special features of the construction of my improved parallel gage, as hereinafter more fully set forth.

My improved parallel gage is represented in the accompanying drawings, in which A represents my improved parallel gage; $p p'$, the upper and lower plates of the same; $l l' l'' l''' l''''$, &c., the links at each side of the same; G, the sliding paper-gage of a paper-cutting machine; T, the table; C, the paper-clamp, and K the knife.

My improved parallel gage consists of an upper and lower plate, $p p'$, connected together by a series of inclined pivoted links at each side, so that the plates, when pressure is applied to them, will approach each other while remaining parallel.

The links are represented in the accompanying drawings at $l l' l'' l''' l'''' l''''' l''''' l''''' l'''''$, and the positions occupied by the plate p and the various links when the parallel gage is compressed are represented by the dotted lines p'' and l'' in

Fig. 1. A similar series of links is placed on each side of the plates, and the two series are connected together by cross-rods $c c' c'' c''' c'''' c''''' c''''' c''''' c'''''$, passing between the plates and join-

ing the ends of the corresponding links. The 50 rods $c c'$, which are placed at the middle of the length of the plates, are journaled to the upper and lower plates, respectively, by boxes $b b'$ riveted to them. The other cross-rods are free to move lengthwise away from the center 55 when the links expand as the plates approach each other. The links l''', l''''' , l'' , and l''''' are simply pivoted together at $d d'$, where they cross each other; but the outer two pairs of links on each side are connected together by rods $r r'$, 60 which pass entirely across the parallel gage and afford points of attachment for the springs $s s'$, by which the plates $p p'$ are forced apart. The cross-rods $c'' c'''$ and $c'''' c'''''$ are limited in their inward movement under the action of the 65 springs $s s'$ by pins $i i' i'' i'''$ projecting from the inner sides of the plates. These pins act as stops to prevent the plates $p p'$ from being too widely separated by the contraction of the springs $s s'$. As the parallel gage is compressed 70 the springs lengthen, and upon the removal of the pressure they cause the gage to return to its usual condition, as shown in full lines in Fig. 1. The ends of the links project slightly 75 beyond the plates, so that the pressure exerted on the parallel gage to compress it acts directly on the links, instead of on the plates. The links are secured to the cross-rods by riveting up the ends of the latter, care being taken to permit the turning of one of the links about the rod at 80 each joint. As shown in Fig. 4, the series of links on one side of the parallel gage bear against the paper-gage G, while the links on the other side afford an even surface, against which the paper P is placed.

When the clamp C is brought down to the position shown by dotted lines C', Figs. 1 and 4, it compresses the parallel gage A, the links thereof extending lengthwise without disturbing the position of the paper, and secures the 90 paper in position upon the table T. The knife K now being forced down on the paper divides it at the desired distance from the front side of the parallel gage.

It is evident that by the use of my improved 95 parallel gage strips of paper may be cut of any desired width less than that of the clamp C, while ordinarily the paper cannot be cut of a

narrower width than the clamp, because the paper-gage cannot be brought closer to the knife than the space occupied by the clamp.

It is evident, also, that my improved parallel 5 gage adapts itself to the thickness of any bundle of paper which it is desired to cut.

In consequence of the arrangement by which the links expand each way from their centers, it will be observed that the friction produced 10 between the links and the paper is equal on both sides of the center of the system of links, so that there is no tendency to disturb the position of the paper during the operation of compressing the gage before the clamp secures the 15 paper in place.

It is obvious that the plates $p p'$ need not extend each way from the center of the link system beyond a sufficient distance to support the stops $i i' i''$.

20 I hereby disclaim the patent of Bell, No. 219,062, September 2, 1879, for bill-files.

I claim—

1. The herein-described compressible parallel gage for paper-cutters, consisting of the 25 plates $p p'$, attached together at each side by diagonal pivoted links and suitable cross-rods, and provided with one or more springs, $s s'$, operating to separate the plates $p p'$, substantially as and for the purposes set forth.

2. The combination of the plates $p p'$, provided with inwardly-projecting stops $i i'$, a series of diagonal pivoted links on each side thereof, connected together by suitable cross-rods, and one or more springs, $s s'$, attached to the cross-rods and operating by contraction to separate the plates $p p'$, substantially as and for the purposes specified. 30 35

3. The combination of the plates $p p'$ with a series of diagonal pivoted links on each side thereof, the said links being arranged to project beyond the plates, substantially as and for the purposes set forth. 40

4. In a compressible parallel gage for paper-cutters, the combination of the plates $p p'$ with a series of diagonal pivoted links provided 45 with suitable cross-rods, attached to the said plates at each side thereof at the center of the series, and arranged to expand lengthwise each way from the center, thereby equalizing the friction between the paper and the links on each 50 side the center of the latter, as and for the purposes set forth.

JOHN B. MURRAY.
